The ornamental design for a beach toy, as shown and described.

DESCRIPTION

FIG. 1 is a front perspective view of the beach toy embodying my new design, which is simulative of a whale shaped tea pot;

FIG. 2 is a front view thereof;

FIG. 3 is a rear view thereof;

FIG. 4 is a top view thereof;

FIG. 5 is a bottom view thereof;

FIG. 6 is a left side view thereof; and,

FIG. 7 is a right side view thereof.

The broken lines in FIG. 5 are included for the purpose of illustrating the bottom surface region of the beach toy that forms no part of the claimed design.
